(Continued)

Primary Examiner — Susan Moon Lee(74) *Attorney, Agent, or Firm* — Polsinelli Shughart PC(57) **CLAIM**

The ornamental design for a bird feeder, as shown and described.

DESCRIPTION

FIG. 1 is a front perspective view of a bird feeder embodying my new design.

FIG. 2 is a right side elevational view thereof, the left side and back elevational views being substantially the same.

FIG. 3 top view thereof; and,

FIG. 4 is a bottom view thereof.
